CONTINUOUS TWISTER AND FEEDER MECHANISM FOR BRUSH MACHINES OR THE LIKE
Joseph T. Gelardi, Yonkers, N.Y., assignor to American Brush Machinery Co., Inc., Mount Vernon, N.Y., a corporation of New York

Filed Mar. 1, 1961, Ser. No. 92,657
22 Claims. (Cl. 300—2)

This invention relates in general to automatic machines for making cylindrical brushes or the like in which transverse members (bristles) are held in spaced relation between twisted longitudinal members (wires), and more particularly to the wire twisting and feeder portions of such machines. The invention is characterized by several novel structures which include (1) a novel wire twisting device that acts against the bristles of a brush-like article rather than the wires thereof; (2) a novel twister-feeder system which is operable to produce continuous twisted brush-like articles that are unlimited in length; (3) a novel wire twister-feed drive device in which the wires of a brush-like article are simultaneously twisted around and driven along their longitudinal axis by forces exerted on bristles held thereinbetween by the twist formed therein; and (4) a novel wire and bristle feeder structure in which the bristles for a twisted brush-like article are deposited directly into the initial standing twist in the wires thereof. The invention is also characterized by other novel structures and structural relationships as set forth in later paragraphs of this document. Although the invention is described herein with particular reference to brushes and brush making machines, it should be understood that the invention is by no means limited to such applications. The invention can also be used to make Christmas tree decorations, dusters, mops, or any other article in which relatively short transverse members are held in spaced relation between relatively long, twisted longitudinal members. For sake of clarity, however, the explanation is limited to brushes with the understanding that the word "brush" means any brush-like article, and that the word "bristle" means any relatively short transverse member, however soft, and that the word "wire" means any relatively long twistable member, however rigid.

Many different machines and methods for producing twisted brushes have been devised in the past, as shown, for example, in U.S. Patent No. 2,742,327, which issued to Theodore Marks on April 17, 1956 for a "Fully Automatic Machine for Making Brushes." In these prior art machines, cylindrical twisted brushes were formed by (1) grasping the ends of parallel wire strands in the chuck of a reciprocating feed carriage, (2) moving the feed carriage to draw out lengths of wire corresponding to a desired brush body length, (3) laying bristles between the wires during the wire feed period, the bristles being held in place between the parallel wires by tension therebetween, (4) rotating the chuck, either during or after the linear feed stroke, to twist the wires together, (5) cutting off the length of twisted wire and dropping the twisted brush body out of the machine, (6) holding the clipped wire ends in position to be grasped for the next feed stroke, (7) returning the reciprocating carriage to the clipped wire ends, and (8) grasping the clipped wire ends and repeating the feed-twist-cut sequence to form another twisted brush body.

Although these prior art machines were quite accurate and efficient in performing their multiple functions, they suffered from all the disadvantages that are inherent in intermittently operated reciprocating machines. Accordingly, one object of this invention is to provide a brush making machine in which twisted brushes are formed by continuous machine processes rather than intermittent machine processes.

2

Furthermore, these prior art machines were limited with respect to maximum brush length, and could only produce as single, fixed brush length in any given production run. Therefore, another object of this invention is to provide a brush making machine which is unlimited with respect to maximum brush length and which can produce brushes of different lengths in a single production run.

Moreover, the production speed of the prior art machines was limited to a relatively low level by the intermittent reciprocating mechanisms thereof and by the complex sequence of operations required to produce brushes therein. Accordingly, another object of this invention is to provide a brush making machine which is adapted to produce twisted brushes faster than heretofore possible in the art.

In addition, the prior art machines required relatively complex timing mechanisms to actuate the various parts thereof in the complex sequence of operations required to produce brushes therein. Accordingly, another object of this invention is to provide a brush making machine in which twisted brushes are formed by a continuous, self-timing process rather than by a sequence of discrete, independent processes which must be synchronized by a separate timing mechanism.

Furthermore, the prior art machines were relatively complex in structure, relatively difficult to adjust, and correspondingly difficult to maintain. Accordingly, another object of this invention is to provide a brush making machine which is simpler in structure, easier to adjust, and easier to maintain than the machines heretofore known in the art.

Also, the prior art machines were relatively costly in manufacture, relatively short-lived in operation, and relatively expensive to maintain. Accordingly, another object of this invention is to provide a brush making machine which is lower in cost, more durable in operation, and less expensive to maintain than the machines heretofore known in the art.

Additional objects and advantages of this invention will become apparent to those skilled in the art from the following discussion of several illustrative embodiments thereof, which will be described in connection with the attached drawings, in which:

FIG. 1 is an elevation view of the wire twisting and feeder portions of a brush making machine in accordance with this invention;

FIG. 2 is an elevation section showing the brush twisting-feed drive arrangement in the embodiment of FIG. 1;

FIG. 3A is an axial section showing a stationary wire twisting and feed drive element which utilizes air jets to produce simultaneous twisting and feeding forces;

FIG. 3B is a radial section of the device shown in FIG. 3A;

FIG. 4 is an axial section showing a first alternate set of brush twisting and feed drive elements which can be used in place of those shown in FIG. 2;

FIG. 5 is an axial section showing a unitary brush twisting-feed drive element which can be used in place of those shown in FIG. 2;

FIG. 6 is an axial section showing a second alternate set of brush twisting and feed drive elements which can be used in place of those shown in FIG. 2;

FIG. 7 is a perspective showing a linear fin structure which can be used in place of the rod structures shown in FIGS. 2 and 4;

FIG. 8 is an axial section showing a spiral fin structure which can be used in place of the helical screws shown in FIGS. 2, 4, and 5;

FIG. 9A is a diagrammatic radial section showing the brush twisting and feed drive elements of FIG. 2 with a

pair of untwisted longitudinal brush wires and lateral brush bristles in the center thereof;

FIG. 9B shows the elements of FIG. 9A with the rotatable rods thereof turned 90 degrees counterclockwise and the helical screw thereof held stationary;

FIG. 9C shows the elements of FIG. 9B after an additional 100 degrees of counterclockwise rotation;

FIG. 9D shows the elements of FIG. 9C after an additional 230° of counterclockwise rotation;

FIG. 10 is an enlarged elevation view of the bristle and wire feed mechanism shown in FIG. 1;

FIG. 11 is an elevation view of one of the wire feed jaws shown in FIG. 10; and

FIG. 12 is a plan view of both of the wire feed jaws shown in FIG. 10.

In general terms, the basic feature of this invention comprises a hollow wire twisting element adapted to twist the wires of a cylindrical brush body passing therethrough. This twisting element can be embodied in a variety of physical forms: it can comprise (1) a rotatable cylindrical shell containing a helical wire screw rigidly attached therewithin, (2) a rotatable cylindrical shell containing a pair of stiff rods running longitudinally through the interior thereof, (3) a rotatable cylindrical shell containing inwardly projecting longitudinal fins, (4) a pair of stiff rods connected together at opposing ends by a pair of rotatable washers, (5) a rotatable cylindrical shell containing an inwardly projecting spiral fin, (6) a hollow motor structure, sans armature, adapted to produce a rotating magnetic field, (7) a fixed cylindrical shell having tangentially-directed air channels through which air jets can be blown, (8) a rotatable cylindrical shell which is substantially smaller in diameter than the brush body, whereby the bristles of the brush body are constricted when driven therethrough such that rotary forces can be applied to the matted bristles from the smooth interior surface of the shell, and (9) any other structure adapted to admit a brush body and to apply rotary forces to the wires thereof.

The wire twisting element of this invention can exert twisting forces against any convenient reacting member which opposes rotary forces coupled to wires of a brush body. This reacting member can comprise a fixed wire guide structure through which the wires for a brush body are drawn, or it can comprise a second wire twisting element which applies rotary forces to the brush wires in opposition to the rotary forces developed by the first wire twisting element.

In accordance with a second general aspect of this invention, the wire twisting element thereof is preferably adapted to simultaneously exert rotary twisting forces and longitudinal feed forces on the wires of a brush body through the bristles thereof. This feature of the invention can be embodied in a rotating helical screw or spiral in structure that works against a fixed wire guide structure, or in a rotating helical screw that works against another rotating helical screw, or in a rotating rod or in structure that works against a stationary helical screw, or in a rotating helical screw that works against a rotating rod or fin structure or in an air-jet structure in which air jets are directed both tangentially and longitudinally against the brush body.

In accordance with a third general aspect of this invention, the wire twisting elements thereof are preferably employed in a progressive twisting battery comprising a plurality of twisting elements adapted to receive a common brush body, each twisting element being operable to increase the twist in the brush body by a predetermined increment of twist to produce a final twist which is approximately equal to the sum of said increments.

In accordance with a fourth general aspect of this invention, the first stage of a progressive twisting battery preferably comprises a first rotary wire twisting element working against a fixed wire guide structure and the second stage thereof comprises a second rotary wire

twisting element working against said first rotary wire twisting element.

In accordance with a fifth general aspect of this invention, the fixed wire guide structure thereof preferably comprises wire guide channels formed in the wire feed jaws from which the wires for a brush body are drawn, the jaws being adapted to oppose the twisting forces applied to the wires of the brush body by a wire twisting element.

In accordance with a sixth general aspect of this invention, the wire feed jaws thereof are preferably spaced with respect to each other, and the bristles for a brush body are preferably inserted between the wires thereof in the space separating the feed jaws therefor.

In accordance with a seventh general aspect of this invention, the wires for a brush body are preferably skewed with respect to each other at the feed jaws from which they are drawn to oppose the twisting forces applied to the wires by a wire twisting element.

In accordance with an eighth general aspect of this invention, the wire guide channels formed in the wire feed jaws thereof are preferably curved in one plane to follow the natural curvature produced by a wire twisting element in the wires drawn therethrough.

In accordance with a ninth general aspect of this invention, the wire guide channels formed in the wire feed jaws thereof are preferably curved in one plane to follow the natural curvature produced by a wire twisting element in the wires drawn therethrough and skewed with respect to each other in a different plane to oppose the twisting forces applied to said wires by said twisting element.

And in accordance with a tenth general aspect of this invention, a brush making machine is preferably formed

by combining the spaced wire feed jaws, bristle feeder, and progressive twisting battery of this invention with a bristle trimmer and wire cutter as shown in FIG. 1. Referring to FIG. 1, continuous wires 20 and 21 are preferably, although not necessarily, driven from storage

reels, not shown, into corresponding guide tubes 22 and 23 by friction drive rollers 24 and 25, which are rotated by means not shown in synchronism with each other to produce a desired wire feed rate. Friction drive rollers 24 and 25 are pressed against their respective wires, the wires being supported by idler rollers 26 and 27. Guide tubes 22 and 23 keep their respective wires from buckling under the driving force, and deliver their respective wires to a pair of spaced wire feed jaws 28 and 29. Structural elements 22 through 27 can be made of any suitable material, and the means for driving rollers 24 and 25 can be any suitable rotary drive means, many of which are well known to those skilled in the art.

It should be noted here that the above described wire feed drive is not essential to this invention because wire feed forces are developed in the wire twisting elements, and these forces can be used to draw wires 20 and 21 from their respective feed rollers without any assistance. In applications where the brush wires are relatively large, however, or the brush bristles relatively soft, it is preferable to use a separate wire feed drive as shown. In other applications, however, it will be preferable to use the wire feed forces from the twisting elements alone because they have the virtue of being self-synchronized. The separate wire feed drive can always be eliminated by making the contact area between the wire twisting elements and the brush bristles large enough for the particular feed load conditions involved in any given application of the invention. The separate wire feed drive is, however, essential in embodiments which use wire twisting elements that do not develop wire feed forces.

The bristles for the brush body are laid between wires 20 and 21 in the space separating jaws 28 and 29 by a picker wheel-pin wheel combination similar to those used in the prior art machines. If desired a multi-slotted wheel may be used in place of the picker-pin wheel com-

bination, the two being functionally equivalent. Suitable bristles 30 are stored in a hopper 31, which may be gravity fed, as shown, but which preferably includes means not shown for applying a feed force to the bristles therein. Bristles 30 are removed from hopper 31 by a rotating picker wheel 32 which is relatively wide in its axial dimension and which contains a picker slot 33 cut into the periphery thereof. Picker slot 33 is preferably fitted with an adjustable bottom 34 which can be raised or lowered to change the bristle capacity of the picker slot 33.

With each revolution of picker wheel 32, picker slot 33 moves across the open end of hopper 31 and receives a charge of bristles which it subsequently dumps on the inclined portion of a bristle guide surface 35. The bristles are then picked up by a dual pin wheel whose symmetrical wheel members are arranged to overlap a portion of picker wheel 32, and whose pins sweep past the bottom of the inclined portion of bristle guide surface 35. Only one half of the pin wheel structure is shown in the drawings (wheel 36 and its associated pins 37) but it will be understood by those skilled in the art that the assembly contains another wheel, not shown, which is identical to wheel 36, and which is mounted on the same shaft with its pins in alignment with pins 37.

The pins of the pin wheel assembly pick up the bristles dumped out of the picker slot 33 and carry them downward along the lower curved portion of guide surface 35, which merges with a pair of bristle guide rails at its lower end. Only one guide rail (rail 38) is shown in the drawings, but it will be understood by those skilled in the art that a second guide rail, not shown, is mounted parallel to guide rail 38. The bristles are driven along the guide rails and are released at the point where the pins of the pin wheel assembly rise above the bristle guide rails.

Picker wheel 32 and pin wheel 36 are driven, by means not shown, at some predetermined speed to lay bristles between wires 20 and 21 at the desired rate, which is dependent on the wire feed rate and the bristle density required in the finished brush. The selection of these speeds, however, is well known to those skilled in the art, as are the other adjustments or structural modifications required to lay bristles at any desired rate between wires 20 and 21. As thus far described, the bristle feed mechanism is similar to the prior art structures, and any suitable prior art materials or techniques can be employed therein.

In accordance with this invention the release point for the bristles is located in the space separating wire feed jaws 28 and 29, preferably at or slightly forward of the vertical centerline thereof, as more clearly shown in FIG. 10. The purpose behind this particular location will become more apparent from a detailed description of wire feed jaws 28 and 29, which are adapted to act as reacting members to twisting forces developed on wires 20 and 21 by a wire twisting element. Jaws 28 and 29 are rigidly attached to fixed frame members 39 and 40, which are rigidly attached to or form a part of the frame structure, not shown, which supports the bristle feed and wire drive assemblies. Each of the jaws has a wire guide channel formed in the surface thereof, as indicated by the dotted lines which follow the surface curvature of the jaws in the elevation view of FIGS. 10 and 11, and which are skewed with respect to each other in the plan view of FIG. 12.

The curvature "r" of these wire guide channels is preferably selected to match the natural curvature that would be produced in wires 20 and 21 at the normal twisting rate thereof. The exact value of curvature used will, of course depend on the specific parameters for any given application, such as the dimensions and resiliency of the wires, wire feed rate, the magnitude of the twisting force, and the like. As shown in FIG. 11, the curvature of the wire guide channels is modified at the wire inlet end to match the angle at which the wires 20 and 21 are delivered to their respective jaws. These angles are preferably in the neighborhood of 45° above or below the horizontal cen-

ter line of the machine, although smaller or larger inclinations can be used, depending on the application. In this particular embodiment wires 20 and 21 are delivered to their respective jaws by wire guide tubes 22 and 23, which are also rigidly attached to frame members 39 and 40. The outlet end of the wire feed jaws is placed slightly forward of the center thereof, where "center" is taken to mean the point on the curvature where the tangent to the curve is horizontal, as indicated by the letter "c" in FIG. 11. The end point is preferably located at the point where the wire curvature begins to deviate substantially from radius "r," and this point, which is defined in FIG. 11 by the angle ϕ , is also dependent on the specific parameters in any given application.

The wire guide channels of the two jaws are skewed with respect to each other so as to oppose the twisting of the wires, as shown in FIG. 12. This skewing serves three purposes, (1) it presses the wires against the sides of their respective guide channels so that they will not slip out when the machine is stopped, (2) it prevents the twisting forces from being communicated back into the wire storage reels, and (3) it spreads the first twist in the wires to form a pocket in which the bristles can be laid. The angle of skew will also vary according to specific conditions, but it should be oriented to oppose the twist of the wires. It should be noted here that the structure of jaws 28 and 29 is identical; the required skew angle is produced by an inverted relation between two identical jaw structures each of whose wire guide channels are inclined at the same angle θ to the longitudinal center line.

The bristles are laid in the pocket formed by the first standing twist in wires 20 and 21 at or slightly forward of the center of jaws 28 and 29, which obviates any tendency of the bristles to slide backward on the downward curve of lower jaw 28. This is done by adjusting pin wheel 36 so that pins 37 rise above bristle guide rail 38 at the center of the jaws. The exact point of release is not critical, but it should not be so far forward that pins 37 catch on the bristles laid in the pocket by a preceding pin. It will be noted that the standing twists in the wire get progressively smaller until they reach a relatively tight twist at some distance forward of the jaws. This smooth progression provides a natural feeder mechanism for feeding the bristles smoothly and uniformly into the tight twist. This progression, which is enhanced by the spreading effect of the skewed wire guide channels, prevents the bristles from being driven backward when pinched between the twisted wires.

It should be noted here that the bristle and wire feeder portions of this invention can be used, if desired, in the prior art machines to simplify the structure and improve the performance thereof. In this case the picker wheel and pin wheel structures would be operated intermittently, in synchronism with the reciprocating carriage, whose chuck would be rotated during the feed stroke to twist the wires as they were drawn from the feed jaws. The skewed guide channels and twisted wires would provide a natural vise for holding the clipped end of the brush, but if further support were needed it could be provided by a collar structure somewhat smaller in diameter than the brush body. This collar could be mounted between the feed jaws and the wire cutting dies to hold the clipped end of the brush in position to be grasped by the reciprocating chuck for the next feed-twist-cut operation.

In accordance with the preferred operation, however, the wires emerging from jaws 28 and 29 are twisted together by rotary forces applied to the bristles thereof in a two-stage progressive twisting battery of this invention, to be described later, which produces a desired degree of twist therein. The bristles of the brush body are then trimmed to a uniform length in a trimmer 41, which can be a rotary trimmer such as employed in the prior art machines, or which can be a stationary trimmer that takes advantage of the fact that the brush body is rotating when it emerges from the wire twisting element of this inven-

tion. Because of this rotation, and the continuous linear feed of the brush body, there is no need to rotate the trimmer 41 as has been done in the past; the natural movement of the brush body will be sufficient in most instances without any rotation of the trimmer. It should be noted also that the trimmer does not necessarily have to follow the wire twisting element; it could be placed between the wire feed jaws and the wire twisting element if desired, thereby trimming the bristles before they enter the wire twisting element. It might, in fact, be desirable to do this in some applications where the bristles encounter appreciable drag in passing through the hollow member of the wire twisting element.

After being trimmed, the brush body is cut into the desired lengths by cutting dies 42 and 43, which can be actuated automatically by any suitable prior art actuators and control circuits. It should be noted, though, that since the brush body is continuously driven, the cutting dies will momentarily interrupt its travel, so that the cutting dies should not be located too close to the trimmer or wire twisting element. A large enough gap must be maintained to permit the brush body to bow out when its travel is interrupted, without reflecting the interruption back into the wire twisting element, whose twisting effect is dependent upon feed rate. If the brush body must be cut close to the trimmer, this is preferably accomplished by guiding the brush body around a turn after it leaves the trimmer and cutting it after it rounds the turn. This arrangement produces a read-made bow which expands when the cutting dies snap shut and contracts when they open. And in cases where the above-noted cutting arrangements are unsatisfactory, the brush body can be cut by means of an electric arc which flashes across the brush body and melts the wires thereof. With an electric arc cutter there would be no interruption of the brush feed, and the brush body could, accordingly, be cut right next to the trimmer. The apparatus for producing and timing this electric arc could be any suitable prior art welding circuit, and the arc could be flashed between a pair of electrodes which flank the brush body, or from one electrode to the wires, which are grounded at their feed jaws and storage reels.

It should be noted, however, that it is not necessary to cut the brush body in short lengths; it could be rolled up on large storage reels if desired, the reels being rotated about one axis in synchronism with the brush feed rate and being rotated about another axis in synchronism with the brush rotation. This can be done, as well understood by those skilled in the art, by mounting the take-up reel in a gimbal structure which allows the reel to simultaneously rotate about two perpendicular axes.

Referring to FIGS. 1 and 2, the progressive twisting battery of this particular embodiment comprises a rotating rod structure which works against jaws 28 and 29 to produce a first increment of twist in the wires, and a rotating screw structure which works against the rotating rod structure to produce a second increment of twist in the wires. The rotating rod structure comprises a pair of rods 44 and 45 which are rigidly attached to end supporting collars 46 and 47, and which rotate independently of the rotating screw. Collars 46 and 47 are fitted with corresponding drive gears 48 and 49 and bearings 50 and 51. This rotating rod structure is journaled through bearings 50 and 51 to frame members 52 and 53, which are attached to or form a part of a supporting framework not shown in the drawings. The rotating rod structure is driven by shaft 54, which is also journaled through bearings to frame members 52 and 53, by means of identical drive gears 55 and 56, which mesh respectively with gears 48 and 49.

Rotating rods 44 and 45 engage the bristles of the brush body, which is centered in the rotating assembly by collars 46 and 47, and apply a twisting force that depends on the spacing between the rods, the stiffness of the brush bristles, and the speed at which the rods are rotated. The

twisting force decreases as the bristles become softer and increases as the space between the rods decreases, whereby the rods should in general be closer together for soft bristles than for stiff bristles. The twisting force applied by rods 44 and 45 is communicated to the brush wires through the bristles, which are rigidly secured to the wires by the twist therein. Thus, the end result of this wire twisting arrangement also serves as an essential link in its operation. If the bristles were not secured to the wires, the rotary forces would not be communicated to the wires, whereby the twist in the wires is a prerequisite to the twisting thereof. This means, of course, that a short length of brush must be twisted by hand to prime the machine when it is initially placed in operation.

The rotating screw assembly, which rotates independent of and faster than the rotating rod assembly, comprises a helical screw 57 rigidly mounted on legs 58 within a cylindrical shell 59, which is journaled to the rotating rod assembly by bearings 60 and 61. The rotating screw assembly is supported by a pair of inwardly projecting collars 62 and 63, which are rigidly attached to corresponding end collars 46 and 27 of the rotating rod assembly. Cylindrical shell 59 is rotated by a gear 64 on drive shaft 54 which meshes with a gear 65 on cylindrical shell 59. Gears 64 and 65 are arranged to rotate the helical screw 57 faster than the rods 44 and 45 therewith at a speed selected to (1) produce a desired linear brush feed rate and (2) a desired increment of twist, as explained more fully below.

The mounting of rods 44 and 45 within screw 57 is not essential to this embodiment of the invention, which could be arranged, as indicated in FIG. 4, by mounting rods 44 and 45 in a separate cylindrical shell 66 which is spaced from cylindrical shell 59. In this case, cylindrical shell 66 would be supported independently of cylindrical shell 59 by means not shown, and would be driven through a single gear 67 which meshes with a drive gear 68. The arrangement indicated in FIG. 4 is not as compact as the arrangement shown in FIGS. 1 and 2, but it is simpler in structure and requires only one gear to rotate rods 44 and 45. The two mounting arrangements, however, are equally effective in producing twist and feed forces, and either can be used in this embodiment of the invention.

The twisting action of rods 44 and 45 is illustrated in FIGS. 9A, 9B, 9C and 9D, which show an untwisted brush body comprising wires 20 and 21 with bristles 69 laterally disposed therebetween. As shown in these figures, wires 20 and 21 are twisted by force couples applied to wires 20 and 21 through bristles 69. In the example shown, the helical screw 57 is held stationary while the rods 44 and 45 are rotated counterclockwise through a complete revolution. This rotates bristles 69, twists wires 20 and 21, and develops feeding forces on bristles 69 as they rotate within the stationary screw. The spreading of the bristles in FIG. 9D results from the twist in the wires. Thus one method of generating simultaneous twisting forces and feed forces is to rotate rods 44 and 45 while holding helical screw 57 stationary.

Another method of generating simultaneous twisting and feeding forces is to use a single rotating screw as shown in FIG. 5. In this arrangement a helical screw 70 is mounted within a cylindrical shell 71 on legs 72. When screw 70 is rotated, through meshing gears 73 and 74, the screw engages the bristles of a brush body therein and imparts simultaneous twisting and feeding forces. The wires of the brush body, of course, must be secured in wire guides or feed jaws which develop a reacting force which allows the wires to be twisted.

In the two stage twisting arrangement shown in FIGS. 1, 2, and 4, rotating rods 44 and 45 work against wire feed jaws 28 and 29 to produce a first increment of twist in the wires, and helical screw 57 rotates faster than rods 44 and 45 to produce a second increment of twist and also to apply feed forces to the brush. In this arrangement, screw 57 functions the same as screw 70 in FIG. 5, but

instead of working against fixed jaws the screw 57 works against the rotating rods 44 and 45. Thus the first increment of twist is produced in the length of wire stretched between the rotating rods and feed jaws, and the second increment of twist is produced in the wire spaced between the rotating rods and rotating screw. The specific speeds of rotation, and the specific screw pitch, will depend on the degree of twist desired in any particular application of this embodiment. The first increment of twist is determined by the speed of the rotating rods and by the feed rate. The feed rate and the second increment of twist are determined jointly by the pitch of the screw, the rotary speed thereof, the diameter thereof, the stiffness of the bristles, the density of and smoothness thereof, and the diameter and twistability of the wires. In general, however, the feed force decreases as the pitch of the screw coarsens while the twist force increases. This relation can be better understood by considering the rotating rod structure to be a degenerate screw having an infinitely coarse pitch. Conversely, the feed force increases and the twist force decreases when the pitch is made finer, and both forces increase as the rotary speed is raised. Thus it can be said in general that the pitch and speed of the screw must be selected in light of the particular brush materials used in a given application to produce the desired brush feed rate and twist. But in any event the rotary speed of the screw must exceed the rotary speed of the rods, and the difference between the two must be great enough to produce the desired twist increment and feed rate for the particular circumstances involved.

FIG. 7 shows a rotating fin structure which can be used in place of the rotating rod structures described above. The rotating fin structure contains longitudinal fins 78, 79 and 80 that project inwardly from a cylindrical shell 81 which is adapted to be rotated by means not shown. Since the bristles entering this structure will be spread, as shown in FIGS. 5 and 9D, any suitable number of projecting fins can be used to engage the brush bristles. The optimum number of fins depends on the bristle stiffness in any given application; with relatively stiff bristles two or three fins are best, but with relatively soft bristles more fins are desirable.

FIG. 8 shows a rotating fin structure which can be used in place of the rotating screw structures described above. In this arrangement an inwardly projecting fin 75 is wound within a hollow cylinder 76 like one of the lands in a rifle barrel. Cylinder 76 is adapted to be rotated by a central gear 77, and it can be journaled and driven as described above for the rotating screw structures. It will be understood that this spiral fin structure generates simultaneous twisting and feeding forces in a manner analogous to the action of the rotating screws, and also that more than one spiral fin could be formed within the cylinder if desired.

FIG. 6 shows a different two-stage progressive twisting arrangement that can be used in the brush twisting machine of FIG. 1. In this arrangement a coarse helical screw 82 twists against the wire feed jaws and a fine helical screw 83 twists against the coarse helical screw. These screws are mounted in corresponding cylindrical shells 84 and 85, which are rotated in the same direction by corresponding gears 86 and 87. Screws 82 and 83 differ not only in pitch, but also in the sense of their winding, i.e., the fine screw 83 is wound so as to feed the brush forward and the coarse screw 82 is wound so as to feed the brush backward. Since the fine screw 83 develops a larger feed force than the coarse screw 82, the brush will be fed forward at a rate determined by the difference in pitch of the screws, and the portion of the brush between the two screws will be in tension due to the backward feed effect of the coarse screw. This tension keeps the brush centered in the two cylindrical shells, and eliminates any tendency of the wire to wobble during the twisting process, as sometimes happens when a rotating rod or fin assembly is used in combination with a rotating

screw assembly. It should be noted that the screws of FIG. 6 are set up for a different direction of rotation than those shown in the other figures, but that they can be adapted for the other direction of rotation by simply reversing the twist of each screw. The screws can be driven at the same speed or at different speeds depending on their pitches, the particular brush materials involved, and the desired feed rate and degree of twist required in any specific application. It will be understood, of course, that spiral fin structures similar to the structure shown in FIG. 8 could be used in place of helical screws 82 and 83 without changing the fundamental operation of this dual screw-twisting battery. In this case the pitch and feed direction of the spiral ledges would be chosen in accordance with the principles described above for screws 82 and 83.

FIGS. 3A and 3B show a stationary twisting-feeding element which utilizes tangentially directed air jets to twist the wires and longitudinally directed air jets to feed the wires. This arrangement comprises a hollow cylinder 88 through which tangential channels T and longitudinal channels L are drilled. An air chamber is formed around cylinder 88 by a concentric cylinder 89, and compressed air is delivered into the chamber through an air inlet 90. In this air drive arrangement the brush is supported by the air from the channels, thereby eliminating all friction between the brush bristle and hollow cylinder 88. The structure does not necessarily contain both the longitudinal and tangential channels; with the longitudinal channels alone it makes a very useful feeding element which can be used to provide or augment the feed force with the mechanical twisting elements of this invention.

In summary, the basic wire twisting element of this invention can be any suitable hollow member which is adapted to receive a twisted brush body and impart a rotary force to the wires thereof. Although several suitable members have been shown in the examples, they are by no means exhaustive of the basic form of this invention. With brushes which have very soft bristles, a simple rotating cylinder might be used without the rod, fin or screw elements shown in the examples. In this case the cylinder would be relatively small in diameter with respect to the brush body, to constrict the bristles thereof, and the rotary force would be applied from the inside surface of the cylinder to the relatively matted bristles therewithin. In brushes which utilize iron, steel or other ferromagnetic bristles, the rotary force could be generated by a rotating magnetic field instead of by a rotating mechanical structure or air jets as shown herein. In this case the brush body would be fed through a hollow field coil structure which is electrically energized to develop a rotary magnetic field such as used, for example, to drive the armature of an induction motor. It should be noted, too, that although the twisting element preferably produces a feed force in addition to its twisting force, this feed force is not essential to the basic form of the invention. The rotating rods, fins, or magnetic fields, which produce no feed forces, can be utilized in combination with any suitable prior art wire feed system or with the air jet feed system of this invention.

From the foregoing description it will be apparent that this invention provides (1) a novel wire twisting element, (2) a novel wire feeding element, (3) a novel wire twisting-wire feeding element, (4) a novel wire and bristle feeder structure, (5) a novel progressive wire twisting battery, and (6) a novel brush making machine formed by combinations of these novel structures.

While the foregoing description sets forth the principles of the invention in connection with specific apparatus, it is to be understood that this description is made only by way of example and not as a limitation of the scope of the invention as set forth in the objects thereof and in the accompanying claims, in which the word "brush" is defined to mean any brush-like article or structure, the word "bristle" to mean any relatively short trans-

verse member, however soft, the word "wire" to mean any relatively long twistable member, however rigid, and the words "brush body" to mean a plurality of wires having bristles spaced thereinbetween, whether twisted or untwisted.

I claim:

1. A brush wire and bristle feeder mechanism comprising a plurality of spaced wire feed jaws each adapted to accommodate a strand of wire, wire feeder means for simultaneously drawing a strand of wire through each of said wire feed jaws, and bristle feeder means for depositing bristles between said strands of wire in the space separating said wire feed jaws.

2. A brush wire twisting element comprising a hollow member adapted to receive a brush body and to permit passage of said brush body therethrough, said hollow member having a brush inlet end and a brush outlet end, and means for applying a rotary twisting force to the wires of said brush body between said brush inlet and brush outlet ends of said hollow member.

3. A brush feeding element comprising a hollow member adapted to receive a brush body and to permit passage of said brush body therethrough, said hollow member having a brush inlet end and a brush outlet end, and means for applying a linear feed force to the wires of said brush body between said brush inlet and brush outlet ends of said hollow member.

4. A brush wire twisting and feeding element comprising a hollow member adapted to receive a brush body and to permit passage of said brush body therethrough, said hollow member having a brush inlet end and a brush outlet end, and means for applying a rotary twisting force and a linear feed force to the wires of said brush body between said brush inlet and brush outlet ends of said hollow member.

5. A progressive brush twisting mechanism comprising first wire twisting means for applying a first rotary twisting force to the wires of a brush body via the bristles thereof, reacting means for applying a first rotary reacting force to the wires of said brush body, said first rotary reacting force being substantially equal in magnitude to said first rotary twisting force but opposite in direction, second wire twisting means for applying a second rotary twisting force to the wires of said brush body via the bristles thereof, and said second rotary twisting force being greater in magnitude than said first rotary twisting force.

6. A brush twisting element comprising a pair of hollow collar structures each adapted to receive a brush body and to permit passage of said brush body therethrough, a pair of rigid longitudinal rods attached between said hollow collar structures, said collar structures being journaled for rotation about their longitudinal axes, and means for rotating said collars and said rods about the longitudinal axis thereof.

7. A brush feed element comprising a hollow cylinder adapted to receive a brush body and to permit passage of said brush body therethrough, a plurality of air-channels formed in the walls of said hollow cylinder, said air-channels being directed along the longitudinal axis of said hollow cylinder, and means for guiding compressed air into said air-channels from the outside of said hollow cylinder.

8. A brush twisting and feeding element comprising a hollow cylinder adapted to receive a brush body and to permit passage of said brush body therethrough, a plurality of air channels formed in the walls of said hollow cylinder, said air-channels being directed across the longitudinal axis of said hollow cylinder and along the longitudinal axis thereof, and means for guiding compressed air into said air-channels from the outside of said hollow cylinder.

9. A progressive brush twisting device comprising first and second hollow, rotatable members each adapted to receive a twisted brush body and to permit passage of said brush body therethrough, means within each of said hol-

low members for mechanically engaging the bristles of said brush body, and means operable to rotate each of said hollow members.

10. A progressive brush twisting device comprising first and second rotatable cylinders each adapted to receive a twisted brush body and to permit passage of said brush body therethrough, a plurality of rigid longitudinal members rigidly attached to the interior of said first cylinder, a rigid helical screw rigidly attached to the interior of said second cylinder, and means operable to rotate each of said cylinders in the same direction with one of said cylinders being rotated faster than the other.

11. A progressive brush twisting device comprising first and second rotatable cylinders each adapted to receive a twisted brush body and to permit passage of said brush body therethrough, a first rigid helical screw rigidly attached to the interior of said first cylinder, a second rigid helical screw attached to the interior of said second cylinder, said first helical screw being wound in one direction and said second helical screw being wound in the other direction, the pitch of said first helical screw differing from the pitch of said second helical screw, and means for rotating each of said cylinders in the same direction.

12. A brush wire and bristle feeder device comprising a plurality of spaced wire feed jaws, a source of wire corresponding to each of said wire feeder jaws, means adapted to guide the wire from each of said wire sources to the corresponding wire feed jaw, means operable to simultaneously draw wire from each of said feed jaws, and bristle feeder means operable to deposit bristles between said wires in the space separating said wire feed jaws.

13. A brush making machine comprising a plurality of wire sources each containing a continuous strand of wire, means operable to simultaneously draw strands of wire from each of said wire sources, a source of bristles, bristle feeder means operable to deposit bristles between said strands of wire, wire twisting means operable to apply a rotary twisting force to said wires through said bristles, and twist reaction means acting against said wires to oppose said twisting force.

14. A brush making machine as defined in claim 13 and also including wire guide means associated with each of said wire strands, said wire guide means being operable to bring said strands of wire together in substantially parallel alignment, and said wire guide means being adapted to oppose said twisting force developed by said wire twisting means.

15. A brush making machine as defined in claim 14, wherein said wire guide means contains a plurality of spaced wire feed jaws, said wire feed jaws being adapted to oppose said twisting force developed by said wire twisting means, and wherein said bristle feeder means is adapted to deposit said bristles in the space separating said wire feed jaws.

16. A brush making machine as defined in claim 14, wherein said wire twisting means comprises a hollow member adapted to receive said wires and said bristles and to permit passage of said wires and said bristles therethrough, means within said hollow member for mechanically engaging said bristles, and means for rotating said hollow member.

17. A brush making machine as defined in claim 16, wherein said wire feed jaws are located between said wire sources and said wire twisting means, and wherein said wires and said bristles are fed from said wire feed jaws through said hollow member of said wire twisting means, and wherein said wire twisting means is operable to twist the length of wires between said wire feed jaws and said hollow member.

18. A brush making machine as defined in claim 17, wherein each of said wire feed jaws contains a wire feed channel, and wherein said wire feed channels are each curved in one plane to accommodate the twist produced in said wires by said twisting means, and wherein said

wire feed channels are skewed with respect to each other to oppose said twist in said wires.

19. A brush making machine as defined in claim 18, wherein said wire twisting means is adapted to apply a linear wire feed force to said wires through said bristles.

20. A brush making machine as defined in claim 19, and also including second wire twisting means for applying a second rotary wire twisting force to said wires through said bristles thereof.

21. A method for making a twisted wire brush or the like, comprising feeding adjacent wires with brush material therebetween through a twisting station while simultaneously applying a force to the brush material in a direction to impart a twist to said wires, thereby locking the brush material between said wires.

22. A method for making a twisted wire brush com-

15
14
prising feeding bristles between adjacent strands of continuously moving wire, applying a force to said bristles in a direction to impart a twist of said wires to lock said bristles therebetween.
